DISPLAY ASSEMBLY AND POSTER HOLDER
David S. Howell, Royal Oak, Mich., assignor to Arlington
Aluminum Company, Detroit, Mich., a corporation of
Michigan

Filed June 27, 1960, Ser. No. 38,337
8 Claims. (Cl. 40—152)

This invention relates to display apparatus and, in particular, to display assemblies and poster holders used therein.

One object of this invention is to provide a poster holder in the form of a border frame which is capable of receiving and holding three-dimensional poster carriers to which the poster design is applied, such as those possessing portions in relief, yet in which the poster carrier is easily and quickly inserted and removed.

Another object is to provide a poster holder of the foregoing character wherein the three-dimensional poster carrier is capable of being inserted from the rear of the border frame without interfering with or incurring interference from the border frame.

Another object is to provide a poster holder of the foregoing character in which the border frame rails are relatively immovable and which is free from hinged border components, latches and other movable parts hitherto necessary for maintaining the poster in its proper position.

Another object is to provide a display assembly including a three-dimensional poster and a poster holder of the foregoing character in which the edge portions of the poster carrier are urged into contact with the border frame and the relief portions project into or through the central opening in the border frame.

Another object is to provide a display assembly as set forth in the object immediately preceding wherein the edges of a backing plate or sheet of slightly greater width than the poster carrier are inserted in channels in the side rails of the border frame after the three-dimensional poster carrier of narrower width has been inserted therebetween for the purpose of firmly holding the three-dimensional poster carrier in its proper position.

Other objects and advantages of the invention will become apparent during the course of the following description of the accompanying drawings, wherein:

FIGURE 1 is a rear elevation of a poster holder adapted to hold three-dimensional posters, according to one form of the invention, with the poster carrier and backing plate omitted to disclose the construction more clearly;

FIGURE 2 is a central vertical section taken along the line 2—2 in FIGURE 1, but with the poster carrier and backing plate inserted to form the display assembly;

FIGURE 3 is a horizontal section, looking upward along the line 3—3 in FIGURE 1, but with the poster carrier and backing plate inserted to form the display assembly;

FIGURE 4 is an enlarged cross-section through one of the side or bottom rails, taken along the line 4—4 in FIGURE 1;

FIGURE 5 is a fragmentary front elevation of the rail portion of FIGURE 4, looking in the direction of the line 5—5 therein;

FIGURE 6 is a fragmentary rear elevation of the rail portion of FIGURES 4 and 5, looking in the direction of the line 6—6 in FIGURE 4;

FIGURE 7 is a vertical section through the top rail of the border frame, taken along the line 7—7 in FIGURE 1;

FIGURE 8 is a fragmentary front elevation of the rail portion shown in FIGURE 7, looking in the direction of the line 8—8 in FIGURE 7;

FIGURE 9 is a fragmentary rear elevation of the rail portion of FIGURE 7, looking in the direction of the line 9—9 therein;

2

FIGURE 10 is an enlarged fragmentary rear elevation of the central portion of the right-hand side rail of FIGURE 1, showing the pivotal mounting of one of the supporting legs thereon;

FIGURE 11 is a fragmentary right-hand side elevation of the side rail portion shown in FIGURE 10; and

FIGURE 12 is a fragmentary central vertical section similar to the lower end of FIGURE 2, but showing a modification of the invention.

Referring to the drawings in detail, FIGURES 1, 2 and 3 show a display assembly, generally designated 18, including a three-dimensional poster carrier P, poster-retaining backing sheet or plate 19 and a poster holder, generally designated 20, according to one form of the invention. The poster holder 20 includes a border frame, generally designated 22, made up of side rails 24 and a bottom rail 26 of similar construction forming three sides of the border frame 22, the fourth side thereof being closed by a top rail 28 of slightly different construction. The rails 24, 26 and 28 are preferably of extruded aluminum and, as described below, may employ the same extrusion, which is subjected to a subsequent cutting operation in order to convert a bottom or side rail 26 or 24 to a top rail 28. As also explained below, the top rail 28 is so constructed on order to permit insertion of the three-dimensional poster carrier to which the poster design is applied as by printing, painting, photography or other known means P. The poster carrier P is illustrated in simplified form as having a flat marginal portion M with edges E and a forwardly-projecting relief portion R joined to the marginal portion M by connecting portions C.

Each of the border rails 24, 26 or 28 has a main part 30 with a fluted front surface 32 for ornamental purposes, a plane rear surface 33, a reversely-turned outer edge flange 34 at the inner edge of the rim flange 36, and an inwardly-projecting flange 38 at the inner edge 40. The flange 38 has an edge 39 (FIGURE 4). The main part of body 30 is in the form of a relatively thin strip which is inclined inwardly from the rim 36 to the inner edge 40 relatively to the plane of the marginal portion M of the poster P. Behind the poster carrier P is placed a relatively stiff backing card or plate 19 of sheet material. The inner edge flange 38 is disposed perpendicular to the plane of the marginal poster carrier portion M. An intermediate flange 42 also projecting inwardly parallel to the inner edge flange 38 is included in all the border rails 24, 26 and 28, and each likewise has an outwardly-directed rib 44 spaced rearwardly a short distance away from the rear surface 33.

In addition, the side and bottom rails 24 and 26 possess an integral extension of the intermediate flange 42 consisting of an angle flange 46 having an inwardly-directed retaining or stop flange 48 disposed parallel to a reference or poster contact plane 49 passing through the edges 39 of the inner flanges 38, and a connecting portion 50 forming the connection with the intermediate flange 42 and joining the edge flange 48 thereto. The stop flange 48 has an edge 51 which is set back from the edge 39 of the flange 38 (FIGURE 4). The angle portion 46 is removed by a cutting operation from the extrusion forming the side or bottom rails 24 or 26 in order to form the top rail 28, as shown in dotted lines in FIGURE 7, and establish a slot 53 between the rib 44 and the angle flanges 46 of the side rails 24 (FIGURE 2). By reason of this construction, the side and bottom rails 24 and 26 are provided with channels 52 for receiving the edges E of the margin M of the poster carrier P, the channel 52 being absent from the top rail 28. The poster carrier P has a width narrower than the distance between the edges 51 of the angle flanges 46 of the side rails 24 so as to slip between them, whereas

the backing plate B is sufficiently wide to extend behind the edges 51 into the channels 52.

Each of the opposite ends 54 of each rail 24, 26 or 28 is cut off at a 45-degree angle (FIGURE 1) in order for the rails to be fitted together to form a rectangular frame, where the rectangular shape of border is desired, as is ordinarily the case. The thus obliquely-cut ends 54 are then united in any suitable manner, such as by welding, thereby providing the open-centered border frame 22 shown in FIGURE 1 with the rectangular central opening 55. The connecting portions 50 of the opposite side rails 24 are drilled coaxially to receive pivot pins, rivets or other suitable headed fasteners 56 (FIGURES 10 and 11) which pass through the correspondingly-drilled upper ends of legs 58 and spacers 60. The spacers 60 also serve to provide a greater wall thickness and reinforcement for the connecting portions 50, to enhance durability. The legs 58 are of such lengths that their lower ends 62 support the border frame 22 at a slight angle of inclination when the legs 58 are swung rearwardly so that they lie at an acute angle to the reference plane 49 (FIGURE 7).

In the use of the poster holder 20 to form the display assembly 18, since the poster carrier P is of less width between its opposite side edges E than the distance between the edges 51 of the angle flanges 46, it is inserted in a rearwardly-tilted position between the edges 51 with its lower edge E in the trough formed by the channel 52 of the bottom rail 26 (FIGURE 2), so that its forwardly-projecting relief portion clears the rearward rib 44 (FIGURE 7) of the upper rail 28, whereupon the user then swings the upper edge of the poster P forward, pivoting on its lower edge E in the channel 52 of the lower rail 26 while the forwardly-projecting relief portion R moves through the central opening 55 of the border frame 22. The front surface of the margin portion M of the poster carrier P is now in engagement with the edge 39 of the rearwardly-projecting inner flanges 38 of the border rails 24, 26 and 28 (FIGURES 2 and 3). Holding the poster carrier P in this position, the user now inserts the lower edge of the backing plate 19 through the slot 53 behind the top rail 28 and slides it downward in the channel 52 of the side rails 24 behind the poster carrier P until its lower edge enters the lower channel 52 of the bottom rail 26. The poster carrier P is now held firmly in position and cannot be removed either accidentally or intentionally as long as the backing plate 19 is in position.

To remove the poster carrier P from the poster holder 20 and thus disassemble the poster assembly 18, the user reverses the foregoing operation by grasping the upper edge portion of the backing plate 19 and removing it by pulling it upward through the slot 53 (FIGURE 2). He then grasps the upper edge E of the poster carrier P and swings it rearwardly between the opposite edges 51 of the angle flanges 46 of the side rails 24, pivoting it around the lower edge E of the poster carrier P in the lower channel 52 of the bottom rail 26. When he has tilted the poster carrier P rearwardly a sufficient distance that the forwardly-projecting relief portion R passes through the opening 55 in the border frame 22 and clears the rib 44 of the upper rail 28, he pulls upward on the poster carrier P and thus removes it from the poster holder 20.

The poster holder 20 of the present invention has also been successfully used with a translucent or transparent poster carrier P, backed up by a light box (not shown) in place of the backing plate or sheet 19. This arrangement forms an illuminated display assembly, which is also intended to be included within the scope of the invention.

The invention contemplates that the poster carrier P, or its relief portion R and connecting portion C may be secured to a permanent or re-usable poster carrier plate M replacing the marginal portion M and of the same relative dimensions and occupying the same position. After use, the temporary three-dimensional poster portion C, R is stripped off the carrier plate M and a new three-dimensional poster portion C, R substituted.

The modified display assembly, generally designated 70 shown in FIGURE 12 is generally similar to the display assembly 18 of FIGURES 1 to 11 inclusive, hence similar parts are designated with the same reference numerals as in FIGURES 1 to 11 inclusive. The modified display assembly 70, as before, has a backing sheet or plate 19, but the edge E of the three-dimensional poster C now rests upon a poster support in the form of a ledge or intermediate flange 72 projecting rearwardly from the bottom rail 74 of the border frame, generally designated 76. The side rails (not shown) corresponding to the side rails 24, also preferably include the ledge or flange 72, but it is removed from the top rail to permit insertion of the poster, hence may also employ the same extrusion. Otherwise, the side rails are like the side and top rails 24 and 28 of the border frame 22 of FIGURES 1 to 11 inclusive.

The operation of the modified display assembly 70 of FIGURE 12 is substantially the same as that described above for the display assembly 18 of FIGURES 1 to 11 inclusive, with the exception of the fact that the edge E of the poster C rests upon the ledge or flange 72 and the ledge or flange 72 of each side rail likewise engages the edge E as a stop flange to prevent it from sliding laterally. Accordingly, repetition of the operation appears unnecessary.

What I claim is:

1. A display assembly comprising a border frame having a top rail, a bottom rail and opposite side rails interconnecting said top and bottom rails, said rails having inner edges bounding a central opening in said frame, lateral and lower retaining members mounted on the rearward sides of said side rails and bottom rail respectively in rearwardly-spaced relationship therewith, said lateral retaining members projecting inwardly and said lower retaining member projecting upwardly, said retaining members having inner edges directed toward said opening, said laterally retaining members defining inwardly-facing channels and said lower retaining member defining an upwardly-facing channel in cooperation with said side rails and bottom rail respectively, a poster-retaining backing member having a width exceeding the distance between said inner edges of said retaining members and having lateral edge portions extending into said channels in retained engagement thereby, and a three-dimensional poster carrier having lateral edge portions with a width therebetween less than the distance between said inner edges of said retaining members disposed between said backing member and said border frame rails, said poster having a lower edge portion extending into said upwardly-facing channel, said poster having a three-dimensional relief portion projecting forwardly from said edge portions at least partway through said opening.

2. A display assembly, according to claim 1, wherein said retaining members include angle flanges having connecting portions secured to and extending rearwardly from said side rails, said angle flanges having retaining portions secured to and extending inwardly substantially perpendicular to said connecting portions.

3. A display assembly, according to claim 2, wherein said angle flanges are integral with said side rails.

4. A display assembly, according to claim 1, wherein said retaining members include angle flanges having connecting portions secured to and extending rearwardly from said side and bottom rails and wherein said angle flanges also have retaining portions secured to and extending inwardly substantially perpendicular to said connecting portions.

5. A display assembly, according to claim 4, wherein said flanges are integral with said side rails.

6. A display assembly, according to claim 4, wherein said rails have outer edges spaced apart from said inner edges and wherein a poster support is mounted on said bottom rail within the upwardly-facing channel intermediate the outer and inner edges thereof and has a rearward

edge terminating forwardly of the retaining portion of the angle flange of said bottom rail.

7. A display assembly, according to claim 1, wherein said rails have outer edges spaced apart from said inner edges and wherein a poster support is mounted on said bottom rail within the upwardly-facing channel intermediate the inner and outer edges thereof in supporting relationship with the lower marginal portion of said poster. 5

8. A display assembly, according to claim 7, wherein said poster support includes a ledge disposed within the upwardly-facing channel thereof and projecting rearwardly from said bottom rail beneath the marginal portion of said poster. 10
